REFRIGERANT CONDENSER COOLER

Lawrence M. Persons, Des Moines, Iowa, assignor
to Penn Electric Switch Co., Des Moines, Iowa,
a corporation of Iowa

Application November 17, 1933, Serial No. 698,476

3 Claims. (CL. 261—92)

The object of my invention is to provide a refrigerant condenser cooler which is simple, durable and comparatively inexpensive to manufacture.

5 A further object is to provide a mechanical condenser cooler as distinguished from the hydraulic type now in general use, one of the main objects of providing such a cooler being to conserve water and heat heretofore wasted.

10 More particularly it is my object to provide a condenser cooler which humidifies the atmosphere and heats it with the heat which is extracted from the condenser coil, the same being effected by using a small quantity of water and operating a fractional horse power electric motor.

15 With these and other objects in view my invention consists in the construction, arrangement and combination of the various parts of my device, whereby the objects contemplated are attained, as hereinafter more fully set forth, pointed out in my claims, and illustrated in the accompanying drawing, in which—

The figure is a diagrammatic view of a refrigerant condenser cooler embodying my invention.

20 On the accompanying drawing, I have used the reference numeral 18 to indicate a refrigerant compressor of the ordinary electric type such as used in butcher shops, large capacity domestic refrigerators and the like.

25 I illustrate an electric motor 12 for driving the compressor and the refrigerating system itself includes an evaporator coil 14 and a condenser coil 16 of ordinary construction. An expansion valve is indicated at 18.

30 Within a room 20, I show a refrigerated display counter 22 such as used in butcher shops, merely by way of illustration, as my refrigerant condenser cooler can be applied to any refrigerating system. Heretofore the condenser coil 16 has usually been cooled by jacketing it with a larger tube and running water continuously through this tube whenever the refrigerating apparatus is in operation. In a three horse power machine, for instance, approximately four thousand gallons of water per day pass over the condenser coil for cooling it by extracting its heat, after which the water itself is permitted to run into the sewer and thus both the water and the extracted heat are entirely wasted.

35 One of the primary objects of my invention is to considerably cut down the quantity of water and to extract the heat and use it in the room 20, or wherever desired, and at the same time humidify the air without any expense other than the cost of the small quantity of water used and

the electricity for operating the air circulating fan requiring but little current consumption.

35 My apparatus includes a receptacle 24 in which the condenser coil 16 is mounted. A liquid 26, preferably water, is contained in the receptacle 24 to absorb the heat from the coil 16. The level of the water 26 is maintained at a predetermined height by means of a float valve 28 connected with the supply pipe 30 and automatically controlled by a float 32.

40 A shaft 34 is rotatably mounted in a housing 36 and has a blower disc 38 secured thereto. Blower blades 40 are mounted on the blower disc 38 and the shaft 34 is driven by a small electric motor 42. For instance, one of about 45 one-sixth horse power has been found satisfactory.

Frictionally receiving the shaft 34 are a pair of spiders 44 spaced from each other and mounted between the spiders is a series of spaced perforated discs 46. All of this is clearly shown in 50 my co-pending application Serial No. 651,521 filed January 13, 1933 which matured into Patent No. 2,054,039 on Sept. 8, 1936.

55 By way of illustration, the room 20 is provided with an outlet register 48 and an inlet register 50. The outlet register 48 communicates with a conduit 52 leading to the central space among the plates 40 so that air is received through the register 48 and driven by centrifugal force 60 through the discs 46 by the blades 40 of the blower. It is then discharged through the register 50 into the room 20.

65 The refrigerating mechanism is controlled in the ordinary manner by an automatic switch 54 having its temperature responsive element 56 subjected to the air to be cooled in the refrigerator 22. The motor 42 can also be connected with the current wires supplying the motor 12 so that it is also controlled by the switch 54 and therefore operable only when the refrigerating mechanism is operable.

70 Other controls can be provided for the motor 42, instead of the switch 54 or in addition to it as desired.

Practical operation

75 In the operation of my refrigerant condenser cooler, the heat from the condenser coil 16 is dissipated into the water 12 and the water thus heated is picked up in the form of a film of moisture on the discs 46. The air being circulated past the discs evaporates the moisture and absorbs the heat of the disc, thus cooling off the portions out of the water 26, which portions 80

- are again re-heated when they enter the water. This causes both heating and humidification of the air and by actual test I have found that between thirty thousand and forty thousand 5 B. t. u. per hour can thus be generated by the condenser cooler and discharged into the room 20 or wherever desired, to either heat some space or furnish part of the heat therefor.
- Since between one hundred twenty thousand 10 and one hundred sixty thousand B. t. u. per hour are all that are required to heat the average five or six room house, it is obvious that the condenser cooler can supply about one-fourth of the heat required so that a furnace or other 15 heating device need supply only three-fourths of the usual amount of heat, while if only one or two rooms are to be heated, the condenser cooler will furnish sufficient heat for that purpose under most circumstances.
- 20 In the winter time, it is also recognized that humidity is desirable and therefore the condenser cooler supplying humidity as it does to the room 20 is a further desirable feature over and above merely economizing on water and 25 utilizing heretofore wasted heat.

In the summer time, of course, it is undesirable to extract the heat from the water 26 for the room 20 and also undesirable to humidify the atmosphere. Therefore dampers 58 and 60 30 can be arranged to coat with registers 62 and 64 or with the registers 48 and 50, as shown by dotted lines, so that when in their full line position the air will circulate through the room as already described, but when in their dotted line 35 positions the air will be taken from, and discharged to, atmosphere. A suitable control handle 66 can be provided in the room 20 to change the dampers as desired. An over-center spring 68 is illustrated to retain them in either of their 40 positions.

Humidifying the air, of course, causes evaporation of the water 26 and it can be replenished automatically by the float valve 28. I have found that my refrigerant condenser cooler requires 45 between one hundred and two hundred gallons of water as against four thousand gallons required by the systems heretofore in use, as already described. This is a considerable saving of water. In the summer time, the saving is even 50 greater, as less water is used with my apparatus.

In the event the water rises too high, in the receptacle 24, it can overflow through a pipe 25 which leads to the sewer or any suitable drain.

I have also found that the refrigerating 55 mechanism operates more efficiently as my condenser cooler can dissipate the heat faster than a reasonable amount of water flowing over the condenser coil as in the old method described. The cost of the current supplied to the motor 60 42 is but a small fraction of the cost of the water supplied by the old method.

From the foregoing description, it is obvious

that much water is saved and all the heat heretofore wasted is used when it is required, as during the winter time or chilly portions of the spring and autumn days.

Some changes may be made in the construction and arrangement of the parts of my device without departing from the real spirit and purpose of my invention, and it is my intention to cover by my claims any modified forms of structure or use of mechanical equivalents, which 10 may be reasonably included within their scope.

I claim as my invention:—

1. The combination with a receptacle, conduit means for directing air through the upper portion of said receptacle, said conduit means having 15 an intake end communicating with a room and with outside atmosphere and having an outlet end also communicating with a room and with outside atmosphere, a condenser having portions in said receptacle, and means for supplying cooling liquid to said receptacle to a level above said condenser; of a device comprising circular disks rotatably mounted in said conduit in the path of air flowing therethrough on an axis substantially parallel to said liquid level, said axis being 20 located a distance thereabove less than the radii of said disks, means for rotating said disks and means in the intake and outlet ends of said conduit to limit communication of said intake end with the room only and said outlet end with outside atmosphere only, or said intake end with outside atmosphere only and said outlet end with the room only.

2. The combination with a receptacle, conduit means for directing air through the upper portion of said receptacle, a condenser coil having portions inclosed in said receptacle and means for supplying a cooling liquid to said receptacle to a level above said condenser; of a device comprising a set of circular disks rotatably mounted 35 in said conduit in the path of air flowing therethrough on an axis substantially parallel to said liquid level, said axis being located a distance thereabove less than the radii of said disks and means for rotating said disks.

3. The combination with a receptacle, conduit means for directing air through the upper portion of said receptacle, a blower for propelling the air through said conduit means, a condenser having portions inclosed in said receptacle and means for supplying a cooling liquid to said receptacle to a level above said condenser; of a device comprising rotatably mounted disks in said conduit in the path of air flowing therethrough and on an axis substantially parallel to 55 the liquid level, said axis being located a distance thereabove less than the radii of said disks, means for rotating said disks, and means for rendering said blower operable upon a predetermined rise in temperature.
